COMPACT OR VANITY CASE

George Rosenberg, New Rochelle, N. Y.

Application September 5, 1934, Serial No. 742,712

9 Claims. (Cl. 132—83)

This invention relates to a case or receptacle, and more particularly to a lady's compact or vanity case.

The primary object of this invention is to generally improve cases or receptacles, particularly flat and preferably circular receptacles, such as are commercially used for ladies' compacts or vanity cases.

A more particular object of the invention resides in the provision of a receptacle made of two different classes of material, for example, a composition selected for its appearance or beauty and metal which is strong and easily worked. It is an object of the invention to obtain the advantages of each of these materials, while doing away with the disadvantages thereof.

Still another object of the invention is to make possible the use of a composition material such as Catalin, which is cast in tubes and yet which may readily be machined for use in the compact.

Still another object is to so construct the metallic portions of the vanity, that they may be used to hold a complete case in assembled relation, without necessitating the application or attachment of screws or other fastening means to the composition material.

A further object of the invention is to make this assembly independent of change in dimension of the composition and metal parts due to unequal expansion or shrinkage. This is important with nearly all compositions, and is especially important with cast phenolics, such as Catalin.

The ordinary vanity case is provided with a mirror on the inside of the cover facing inwardly, this being exposed when the case is opened. In accordance with a further object and feature of the invention, the bottom of the vanity includes a mirror facing outwardly, which is valuable for use as a hand mirror without opening the case. This mirror makes unnecessary the extra mirror usually carried by a woman in her handbag. Because the mirror is located at the bottom of the case, the cover at the top of the case may be suitably decorated or adorned to beautify the same.

To the accomplishment of the foregoing and such other objects as will hereinafter appear, the invention consists in the receptacle elements and their relation one to the other as are hereinafter more particularly described in the specification and sought to be defined in the claims. The specification is accompanied by a drawing, in which:

Fig. 1 is a perspective view showing a compact

or vanity case embodying features of the invention;

Fig. 2 is a similar view with the cover open;

Fig. 3 is an inverted plan view showing the bottom of the case;

Fig. 4 is a section taken in elevation through the case with the cover open; and

Fig. 5 is a plan view of a composition ring forming a part of the complete receptacle.

Referring to the drawing, the case or receptacle comprises an outer ring R and an inner case C fitted therewithin. Ring R is preferably made of any moldable plastic or suitable composition material which is selected for its beautiful appearance. In the sample illustrated in the drawing, ring R is made of transparent Catalin, which resembles glass in appearance and which is not fragile. Catalin is particularly valuable for the present purpose because it is available in a large variety of colors with or without variegated effects, closely simulating marble, onyx and other valuable natural materials. The use of Catalin is limited because it can not be molded, but must be cast. In accordance with the present invention, ordinary tubular Catalin stock is used, the tube being cut into rings of desired cross-section by a simple machining process. In the present case, ring R is approximately triangular or wedge-shaped in cross-section as best shown in Fig. 4. The inner wall 12 is cylindrical.

The case C preferably comprising a circular metallic lining wall 14, is fitted within ring R and held in place by outwardly turned top and bottom flanges 16 and 18. Lining wall 14 is permanently closed at the bottom preferably by a bottom wall including an outwardly facing mirror 20 and is openably closed at the top by a suitable cover generally designated 22. It will be manifest that with this construction, case C is held within ring R without necessitating the use of screws or other fastening means in the composition material and without necessitating forming the composition material to an intricate shape such as could be economically produced only by molding. It will also be apparent that the ring R can be securely clamped between the opposed flanges 16 and 18 even though appreciable clearance is provided between the inner wall 12 of the ring and the outer face of metallic wall 14. This is important because of relative expansion or shrinkage of the composition and metallic materials of the case.

In order to simplify assembly of the complete compact, I prefer to form the inner case C of upper and lower portions which telescope together

with a tight frictional fit. Specifically, the upper portion includes a flanged ring comprising the wall 14 and flange 16, to which ring the cover 22 is hinged. The lower portion comprises a flanged ring including a circular wall 24 and reversely bent flange 18 which projects outwardly and terminates at the inwardly directed flange 26. The bottom 20 which is preferably a circular mirror with a suitably beveled edge 28 is supported on flange 26, and is held in place by a metallic disc 30 which is forced downwardly within the wall 24. A layer of backing material 32 is preferably inserted between mirror 20 and disc 30 in order to protect the mirror.

15 It will be evident that to assemble the compact it is merely necessary to slide the upper portion of inner casing C including the cover 22, within composition ring R and to then force the lower portion of inner case C within wall 14 from the opposite side of the ring until the ring is tightly clamped between the opposed flanges 16 and 18. The ring is preferably peripherally recessed at 34 and 36 to receive flanges 16 and 18. These recesses are formed as a part of the turning or 20 machine operation which shapes the ring. An additional recess 38 is preferably formed to provide clearance for the hinge 40 supporting the cover 22.

Cover 22 comprises a sheet metal ring 42 having an inwardly turned flange 44 which supports a mirror 46. The top of the cover is preferably formed by an upwardly convex suitably decorated disc of material 48. This disc is held in place, by a circular channel member 50 which extends 25 around the outwardly projecting flange 52 of ring 42. Channel member 50 is cut away at 54 to provide clearance for an arm 56 formed integrally with ring 42 and bent to form one half of hinge 40. Channel member 50 is also cut away at 30 58 to form clearance for an outwardly projecting finger piece or tab 60 which facilitates opening of the cover. A dot or teat 62 is preferably struck outwardly on ring 42 and mates with a recess or aperture 64 on lining wall 14 to normally hold the cover in closed position.

In the present case, the top 48 is made of celluloid or like transparent material, and an appropriate picture is printed upon a suitable paper disc 70 mounted on backing 72 and exposed beneath the top 48. A further filling or backing piece 74 may be used to hold the parts in desired location. The outer surface or top 48 may have applied thereto, scroll-like metal foil decorations 76 which act to frame the picture 72.

55 It will be understood that the cover may be constructed in a variety of ways, for it does not constitute an essential part of the invention other than the preferable use of outside ornamentation and an inside mirror. This outside ornamentation is made possible because the outside mirror 20 is located at the bottom of the vanity case.

60 It is believed that the mode of constructing as well as the many advantages of my improved receptacle or vanity case will be apparent from the foregoing detailed description thereof. The casing is made up of contrasting materials, which give the same a beautiful appearance. These materials are joined together without difficulty because of the mode of assembly of the upper and lower parts of the case, which are telescoped 65 tightly together within the composition ring, or more particularly, because the ring is anchored in place between opposed peripheral flanges. A highly desirable composition material like Catalin 70 may be advantageously employed despite the

disadvantages ordinarily attendant upon the attempted use of this material. The outside mirror may be used as a hand mirror, yet does not detract from the ornamental appearance of the compact.

5 It will be apparent that while I have shown and described my invention in a preferred form, many changes and modifications may be made in the structure disclosed without departing from the spirit of the invention defined in the following 10 claims:

I claim:

1. A receptacle comprising an outer ring of composition material and an inner case fitted 15 within said ring, said case comprising upper and lower parts having axially directed walls dimensioned to telescope within one another with a tight friction fit and further comprising means for engaging the outer ring to hold said inner case in position.

2. A receptacle comprising an outer ring of composition material, and an inner case fitted within said ring, said case comprising upper and lower parts having axially directed walls dimensioned to telescope within one another with a 25 tight friction fit and further comprising radially projecting flanges for engaging the outer ring, a bottom wall at the lower part of the case, and a cover hinged to the upper part of the case.

3. A compact or vanity comprising an outer 30 ring of composition material selected for appearance, the inner wall of said ring being cylindrical, and an inner case fitted within said ring, said case comprising upper and lower parts having axially directed walls dimensioned to telescope within one another with a tight friction fit and further comprising radially projecting flanges for engaging the outer ring to hold said inner case in position, a bottom wall forming a part of the lower part of the case and closing the 40 same, and a cover hinged to the upper part of the case for closing the same.

4. A receptacle comprising an outer ring, and an inner case fitted within said ring, said case including flanged metallic bottom and top rings 45 telescoped together with a tight frictional fit, a bottom attached to said lower ring, and a cover openably mounted on the top ring.

5. A compact or vanity comprising an outer ring made of a composition selected for appearance, and an inner case fitted within said ring, 50 said case including flanged metallic bottom and top rings telescoped together with a tight frictional fit, a bottom fitted in the bottom of said lower ring, and a cover hinged to the top ring.

6. A compact or vanity comprising an outer ring made of a composition selected for appearance, and an inner case fitted within said ring, 60 said case including bottom and top rings telescoped together with a tight frictional fit, a mirror fitted in the bottom of said lower ring and facing outwardly, means holding the mirror in place and a cover hinged to the top ring.

7. A compact or vanity comprising an outer ring made of Catalin, and an inner case fitted 70 within said ring, said case including flanged bottom and top rings telescoped together with a tight frictional fit, a mirror fitted in the bottom of said lower ring and facing outwardly, a bottom disc forced into said bottom ring and holding the mirror in place, a cover hinged to the top ring, a mirror mounted within said cover 75

facing inwardly, and means decoratively finishing the outer wall of the cover.

8. A receptacle comprising an outer non-metallic ring and an inner metallic case fitted within said ring, said case comprising upper and lower parts telescopically assembled with said ring by being inserted therein from opposite sides thereof and further comprising means for engaging the outer ring to hold the inner case parts in assembled position.

9. A receptacle comprising an outer non-

metallic ring and an inner metallic case fitted within said ring, said case comprising upper and lower parts telescopically assembled with said ring by being inserted therein from opposite sides thereof and including means for engaging the outer ring to hold the inner case parts in assembled position, and a mirror fitted in the bottom of said lower case part and facing outwardly.

GEORGE ROSENBERG. 10
